CONDENSATION DRAIN

William Queirolo, San Francisco, Calif.

Application February 5, 1944, Serial No. 521,187

2 Claims. (Cl. 126—307)

This invention relates to a condensation drain, particularly one intended to be used in a stack carrying wet gases from a fuel burner.

In the operation of a fuel burner, water is necessarily present in the products of combustion, due to the oxidation of hydrogen present in the fuel to form water. Particularly in those instances where the burner gases are conducted through relatively light pipes having little heat retaining capacity, so the atmosphere can quickly cool gases in the pipe, water condenses and collects. Instances are known where the water has actually filled an elbow, cutting off gas flow through the pipe. Other instances are known where the collected water has drained back and has put out the fire.

It is in general the broad object of the present invention to provide a simple condensation drain which can be placed in a stack to remove condensate forming and draining down the stack.

Another object of the present invention is to provide a relatively simple connection between adjacent pipe sections which can serve as a condensate drain and also a connection between the pipe sections.

The invention includes other objects and features of advantage, some of which, together with the foregoing, will appear hereinafter wherein the present preferred form of condensate drain of this invention is disclosed.

In the drawing accompanying and forming a part hereof, Figure 1 is a side elevation partly in section illustrating a condensate drain of this invention employed between adjacent pipe sections.

Figure 2 is a plan view of the condensate drain of this invention.

Referring to the drawing, I have shown adjacent pipe sections 5 and 6. These can comprise any of the usual sheet-metal or composition pipes usually employed to carry wet gases. These pipes are ordinarily of the same internal and external diameter and are usually connected together by some form of coupling, or by brazing.

In accordance with this invention I provide a condensate drain in the form a frustum of a cone, as indicated generally by numeral 7 in the drawing. This structure is usually made of sheet metal and is larger adjacent its base 8 than at the top portion 9, so that the top portion fits within pipe 5 while the bottom portion 8 slips over the top of pipe 6. To permit condensate collecting in pipe 5 to collect and drain out of the stack I preferably corrugate the top section 9 as I have indicated at 11. The top pipe 5 rests upon the ribs of the corrugation; any moisture passes down through the grooves of the corrugation to the outside of the stack. If desired, a rim 12 can

be formed on the base of the drain to collect the condensate, and if desired, the condensate collecting in the rim 12 can be led away through a suitable drain pipe, not shown.

5 While I have disclosed that the drain is positioned in a vertical pipe, it will also operate satisfactorily in angularly positioned pipes. In addition, it can be used to provide a connection between pipes 5 and 6 even though they are not on 10 the same longitudinal axis.

In addition to acting as a condensate drain, the device of the present invention assists the draft through the stack provided by pipes 5 and 6, permitting air to enter and create a draft 15 through pipe 5. The presence of the condensate drain in the stack also tends to offset a gust of wind blowing back down the stack and putting out a burner flame.

While I have so far described the device as a 20 condensate drain only in connection with burner gases it is not limited to this application. For example, it can be used to advantage in a fume vent line from a ventilated hood to separate grease or other condensate from the gas and 25 prevent it from running back toward the gas source.

Condensate is collected in the rim 12, as I have 30 mentioned. This rim can be turned in toward the base 8 or it can even be formed at a suitable angle to the base to permit the drain to be fastened to a roof to provide a roof flange for supporting the drain and pipe section 5.

I claim:

1. In combination, a first pipe adapted to lead 35 from a wet gas source, a second pipe extending beyond said first pipe, and means connecting said pipes and comprising a frustum of a cone, one end being of larger diameter than the first pipe and positioned over an end of the first pipe 40 and extending into an end of the second pipe, the side wall of said frustum being corrugated to provide a plurality of liquid passages from said second pipe to the atmosphere.

2. A flue pipe construction comprising a first 45 vertical flue pipe, a second vertical flue pipe above the first pipe, and a connection joining said pipes comprising a frustum of a cone having a corrugated side wall, one end of said cone frustum being of a larger diameter than the first pipe, said 50 connection being positioned with said wall over the end of the first pipe and extending into the second pipe, said corrugations being of such depth and extent as to provide a plurality of liquid passages from the second pipe to the atmosphere when the connection is in that position in 55 which it joins said pipes together.

WILLIAM QUEIROLO.
